UNITED STATES PATENT OFFICE.

GEORGE H. DONALDSON, OF WEST HARTFORD, CONNECTICUT.

NIPPLE FOR NURSING BOTTLES.

Application filed July 6, 1926. Serial No. 120,577.

This invention relates to those nipples which are attached to the mouths of bottles from which liquid food is served to babies, and particularly such nipples as are adapted 5 for attachment to wide mouth bottles, although of course it may be made in sizes which will fit small mouth bottles.

The object of the invention is to provide a simple and readily cleaned nipple which 10 can be easily applied to or removed from the bottle neck and which has a teat that is soft for and can be conveniently applied to the mouth of the infant so that the entire food contents may be withdrawn without making 15 it necessary to tip the bottom of the bottle substantially higher than the top. The nipple also has means which allows the admission of air as the food is withdrawn so as to ensure a continuous and easy outflow of food 20 without collapse of the nipple, which means is so arranged that there will be no leakage of food when an infant is being fed.

This object is attained by making a cap-shaped body of somewhat elastic material, as 25 rubber, of a size that will tightly fit the neck of the bottle which is to be used, and extending the soft teat with the feeding hole obliquely with relation to the axis of the bottle from the top and near one side of the 30 body of the nipple. The body is also provided with a protuberance having an air perforation, which protuberance extends angularly from the side of the body opposite the feeding teat near the rim, which rim, adjacent to the protuberance, has a tab that facilitates the application to and removal from 35 the bottle of the nipple.

In the accompanying drawings Fig. 1 shows a section of a nipple that embodies the 40 invention, applied to the upper end of a wide mouth nursing bottle. Fig. 2 shows an elevation of the same.

The cap-shaped body 1 of the nipple which is generally circular in outline has an inwardly extending rib 2 around its rim which rib is of a size and shape to extend under and tightly grasp the bead 3 around the mouth of the bottle 4. The feeding teat 5 with a perforation 6 at its tip is arranged to 45 project from the top of the body near one side. This teat has the commonly approved

shape, and it may be slightly thinner and more flexible than the body of the nipple. The teat extending in this manner may be readily inserted into the mouth of the infant 55 to be fed and being at the top and on one side and extending angularly with relation to the axis of the bottle, all of the food can be withdrawn from the bottle without inclining the bottom of the bottle to any substantial degree above horizontal.

Extending from the side of the body opposite the teat and near the rim is a rounded protuberance 7 having a perforation 8. This protuberance is shown as extending substantially at right angles to the axis of the bottle. If the bottle is filled practically full of liquid food, when it is turned over and the feeding teat presented to the infant the opening through the protuberance will be above 70 the level of the liquid so that there will be no leakage, and as the food is withdrawn air will enter through the hole in the protuberance and permit the withdrawal of fluid without undue effort on the part of the infant. The entrance of air in this manner 75 also eliminates the possibility of any collapse of the nipple, consequently the nipple can be made of comparatively thin elastic or flexible material. Extending from the rim of the body adjacent to the protuberance there may be a tab 10 which affords means that can be easily grasped by the thumb and finger when the nipple is being applied to or removed from the bottle neck.

The invention claimed is:—

A nipple formed of elastic material and adapted to be applied to the neck of a wide mouth bottle, which nipple comprises a cap-shaped body portion, a perforated feeding teat extending obliquely with relation to the axis of the cap from the closed top near one edge of the body portion, a protuberance with a perforation in its end extending at right angles with relation to the axis of the cap from the body portion near the rim, at the open end on the side opposite from the feeding teat, and means extending from the edge of the body portion near the protuberance for facilitating the application to and removal from a bottle of the nipple.

GEORGE H. DONALDSON.
